UNITED STATES PATENT OFFICE.

LINUS YALE, JR., OF PHILADELPHIA, PENNSYLVANIA.

LOCK.

Specification forming part of Letters Patent No. 32,331, dated May 14, 1861; Reissued April 28, 1863, No. 1,469.

To all whom it may concern:

Be it known that I, LINUS YALE, Jr., of the city and county of Philadelphia and State of Pennsylvania, have invented a new and Improved Method of Constructing Locks for Banks and other Purposes; and I do hereby declare the following to be a full and exact description of the same, reference being had to the annexed sheet of drawings.

The nature of my invention consists in making such an arrangement of parts as to render unavailing any attempts to ascertain the differences between or position of the "tumblers" "levers" or "stops."

To enable others skilled in the art to make and use my invention, I will proceed to describe its construction and operation.

The same letters refer to the same parts in all the figures of the drawings.

Figure 1, is a plan of the lock with the cover removed: the parts are represented in the locked position.

A. is the case; B. the bolt; C. the talon-plate attached to the bolt, and by which it is shot back and forth.

D. is a geared wheel carrying with it the ratchet wheel E. and the pin e^1 also shown in section Fig. 6. This wheel D. is actuated by the key or driving wheel F. which is pierced through its center for the key-hole f to receive the pod O. and square part of n , of the key shank N. Fig. 2. The pod O. passes completely through the key wheel F. into a chamber immediately behind it in the case where it remains stationary, while the handle is being revolved and through it the key or driving wheel F. The pod O. is jointed to the handle by means of a swivel pin in the ordinary "swivel key" manner.

G. is the draw-down-plate which receives vertical motion from the pin e^2 working in the curvilinear talon notch made for that purpose as indicated by the dotted lines under the wheel D. This draw down plate has a hardened punch g attached to its lower end which when the plate is elevated enters the key pod O. and drives the frame of bits P. Fig. 3 out and carries them up against the ends of the primary tumblers (or key tumblers) I Fig. 5. (and also indicated by dotted lines in plan Fig. 1 as being behind the parts L. G. D. and E.) thereby raising the said tumblers to different heights according to the varying lengths

of the key bits. The piston g passes fully across the key chamber before the tumblers are raised to their full height, thereby closing the approach to them or in other words the passage through which it has driven the key frame and bits, so that no instrument however small can be inserted to feel of the said tumblers, at the time when the bolt can be moved so as to bring the edges of the primary and secondary tumblers into contact for the purpose of feeling out their positions, by what is known as the "tentative" method of picking. This draw down plate has also attached to the under side of its upper end as indicated by dotted lines marked g' a projection or hook for the purpose in its downward movement of pulling or drawing down the tumblers I. to their normal position, which movement also pushes down the frame and bits of the key into the pod O. ready to be withdrawn with the handle N.

The primary tumblers have only a vertical movement lying in guides in the case of the lock. The secondary tumblers H. are partially shown in place and one fully shown in Fig. 4. They work vertically in suitable guides in the bolt and are also moved back and forth with the bolt. In their unlocked position the tenons of the secondary tumblers are embraced in the recesses of the primary tumblers as usual in all permutation locks and thus both are raised and depressed together. But when in the locked position the shot out position of the bolt separates them and holds the secondary tumblers out of reach of the primary ones, in the relative positions indicated in the plan and also in Figs. 4 and 5. The ends of the tenons opposing themselves to some parts of the edges of the tumblers I. These ends cannot however be brought into actual contact for the purpose of feeling out their positions, until the draw down plate is lifted to its fullest height, when the key hole is crossed by the punch g and the access to the tumblers cut off thereby completely, as above described. The secondary tumblers in their locked position are anchored in their "positions" by the stationary knife edge K. entering some one of the notches (see H. Fig. 4) which are cut relatively to suit the various lengths of the bits of the key.

All the parts above described are well known and some of them secured to me by

patent of May 6th 1851 and June 12th 1860. But the following device is added for a protection against a process applicable to nearly all kinds of locks by which they can 5 be securely and easily picked.

It is impossible to construct tumblers or stops so exactly alike in width as that there shall be absolutely no variation. Therefore by the application of an index which shall 10 multiply a few thousand times those minute differences become discernible and palpable and will enable a skilled manipulator to tell which tumbler takes the most strain and thereby also enable him to adjust it 15 and afterward by the same process the remaining ones, to a position to take the stump or fence tumblers as the case may be.

E. Figs. 1 and 6 is a ratchet wheel made fast to a revolving crank pin in the wheel 20 D. which pin is made in two parts e' and e^2 secured together and fast to the ratchet E. The pin e' is, on its upper end, shouldered down about one tenth of an inch whereby I am enabled to make it about one sixteenth 25 of an inch smaller and that much eccentric without over reaching the concentric part. (See e' Fig. 1.)

M. Fig. 1 is an arm inserted in the top of a post of the case which holds it in position 30 to turn the ratchet by means of its little pawl or click, whenever the wheel D. revolves to the right carrying the ratchet with it. The ratchet wheel is held in the position that contact with M. has placed it 35 by another stationary pawl or catch d Figs. 1 and 6. Thus it is seen that at every movement toward unlocking, the ratchet, and of course the crank pin e with its eccentric top e' is revolved more or less according to 40 the amount of motion given to D.

The talon plate C. has on its right hand craw or corner a little spot wasted away so that the eccentric part of the pin e' must strike first but when the motion 45 thereby communicated is nearly completed the concentric part strikes the unclipped part and finishes the movement as perfectly as though the whole pin were concentric, and the shoulder or craw plump and full. 50 Thus as the eccentric pin head strikes each time a different side it allows the wheel D and therefore the driving wheel F to rotate to a different point each time by which means the index which may be attached to the lock 55 would so vary as to utterly confuse the operator and negative all attempts to detect the "positions."

To unlock. Insert the key. Turn the handle to the left and it communicates motion 60 to the wheel F through that to the wheel D. and through both by means of the lower end of the crank pin e^2 to the draw

down plate G. which it elevates thereby similarly elevating the punch g which drives the bits P out of the pod O. and up against the ends of the primary tumblers I until the frame and bits are completely within the guides of the primary tumblers and the punch has followed them sufficiently to close up all access to them and has thereby fully 65 imprinted the form of the key upon said tumblers. Then the pin e' with its eccentric top has reached the talon and started the bolt backward in its movement also carrying the fence or secondary tumblers into the 70 embrace of the gating in the primary ones and relieved them from the anchorage on the knife edge K so that when the motion of the bolt backward is completed and the primaries have complete possession of the 75 secondaries the crank pin e^2 again engages in the drawdown plate G. and through it restores both the primary and secondary tumblers and also the key bits to their first position. The withdrawing of the key handle 80 discovers the key bits in the pod O. as when the key was inserted. To lock. Insert the key again. Turn it to the right and the reverse movement will be given to the wheels and bolt but a precisely similar one to the 85 drawdown plate and punch by whose means the key bits are again elevated and impressed on the tumblers and fence tumblers when the forward movement of the bolt carries the latter to their anchorage on the 90 fence-knife edge K and when the crank pin 95 e' has completed that duty and left the talon plate C. the lower end of it engages again in the drawdown plate to again move it, and its ratchet wheel E is revolved partially by catching on the finger of the arm M. bringing a different side of the eccentric 100 in position to bear first when it is again used.

This peculiar arrangement of parts may be applied to almost any form of lock, or 105 its equivalent to this form in a different manner to effect substantially the same object i. e. a varying indication of the movements when an attempt is made to ascertain its positions by index. This arbitrary varying of distances may be put between other parts with precisely the same results. 110

Having thus described the nature and purpose of this my invention, what I claim as new and desire to secure by Letters Patent 115 is—

The application to locks of the parts E. e' . e^2 . d. and M or their equivalents for the purpose and object substantially as described.

LINUS YALE, JR.
